PAINT BRUSH HOLDER

Filed April 26, 1945

UNITED STATES PATENT OFFICE

2,445,224

PAINTBRUSH HOLDER

Stanley Kubiak, Bayonne, N. J.

Application April 26, 1945, Serial No. 590,410

8 Claims. (Cl. 206—15.1)

1

My invention concerns improvements in the art of maintaining paint brushes and the like in proper serviceable condition for effective use and has for one of its objects the provision of a novel construction and arrangement whereby paint brushes, after use, may be cleaned, stored and maintained in an economical and efficient manner so as to prolong the life of said brushes and which at the same time shall be so designed that it may be adapted for reclaiming oil and paint materials from the brushes.

Another object of my invention is to provide a paint brush device of the character described which shall comprise relatively few and simple parts, which shall be relatively inexpensive to manufacture, easy to assemble and which shall represent a general improvement in the art.

Other objects of my invention will become apparent as the description proceeds, or will hereinafter be pointed out.

In the accompanying drawing,

Fig. 1 is a vertical cross-sectional view of a paint brush device constructed and arranged in accordance with my invention;

Fig. 2 is a cross-sectional view taken substantially along the line 2—2 of Fig. 1;

Fig. 3 is a cross-sectional view taken substantially along the line 3—3 of Fig. 1;

Fig. 4 is a cross-sectional view taken substantially along the line 4—4 of Fig. 1; and

Fig. 5 is an enlarged cross-sectional view taken substantially along the line 5—5 of Fig. 2.

Referring now in detail to the drawings I have illustrated a paint brush device constructed and arranged in accordance with my invention and comprising a container 10, open at the top which may take the form of a pail, a paint can or other similar suitable receptacle for holding paint material. Disposed within the pail 10 is an annular platform supporting member 11 which may be made of any suitable relatively rigid material of the nature of metal or the like and which is of smaller diameter than that of the said pail 10 and of a predetermined height.

The member 11 rests freely on the bottom wall 10a of the pail 10 and is adapted to support on the top rim thereof a screen member 15 of any suitable material unaffected by the paint materials and of any desired mesh for the purposes intended. The diameter of the screen member 15 is substantially equal to that of the inside diameter of the pail 10.

In accordance with my invention paint brushes which have been used on a painting job may be placed in the pail 10 with the bristle portions

2

thereof resting on the screen 15. In this way the drippings from the brush will fall through the screen to the bottom of the pail. The height of the member 11 is such that the bristles of the brushes will not be permitted to rest in a pool of sediment resulting from the drainage from the brushes. When a supply of brush cleaning solution, such, as for example, turpentine, is placed in the pail 10 there will be formed a sediment of paint at the bottom of the pail which may be reclaimed and used again.

In order that the annular member 11 shall not form a barrier for the free distribution of flow of the turpentine or paint drippings, I provide a series of concaved areas 11b extending upwardly from the bottom edge of the said member 11, as clearly shown in Fig. 1 of the drawings.

Since, as above described, the paint drippings from the brushes collect at the bottom of the pail 10, it is evident that the bottom edge of the supporting member 11 may become caked to the bottom of the pail. To break the encrusted hold of the screen support 11 on the pail 10, so that the said support 11, screen 15 and pail 10 may be cleaned, I provide the following device.

The annular member 11 may be formed from a flat strip of material and bent in the form of a ring with the opposite edges terminating in a pair of flanges 20 extending outwardly to substantially reach the wall of the pail, as shown in Fig. 4 of the drawings. Pivotedly mounted at the lower end thereof between the flanges 20 by means of the pivot 22 is a vertically disposed handle member 21 terminating in a hand gripping portion 21a projecting above the top of the pail 10.

The portion of the handle 21b adjacent the bottom end thereof is forwardly cammed and is adapted to rest upon the bottom wall 10a of the pail 10.

A spring 25 having one end thereof attached to the handle portion 21b and the opposite end fixed to the supporting member 11 normally urges the rotation of the said handle 21 in a clockwise direction as viewed in Fig. 1 to dispose the said handle 21 out of the way and up against the wall of the pail 10.

The screen member 15 is provided with a notched portion 26 extending inwardly from the periphery thereof to accommodate the passage of the handle therethrough and to permit pivotal movement of the handle as will presently be explained. To prevent undesired tilting or displacement of the screen 15 the same may be anchored to the support 11 in any desired well known

manner, such as, for example, the screws 30 passing through openings 31 in the screen 15 and threadedly received in the supporting member 11 (see Fig. 5).

It is thus seen from the above described construction that should the supporting member 11 become caked to the bottom of the pail, it is merely necessary to grasp the handle portion 21a and pivotally pull the same in a counterclockwise direction (as viewed in Fig. 1). This will cause the cam portion 21b of the handle to push against the bottom wall 10a of the pail to cause the supporting member 15 to break away and free itself. It is noted that the notched or concaved areas 11b will reduce the amount of surface contact between the support 15 and the bottom wall 10a and thus facilitate the freeing of the support 15.

In accordance with the provisions of the patent statutes, I have herein described the principle and operation of my invention, together with construction which I now consider to represent the best embodiment thereof, but I desire to have it understood that the structure shown is only illustrative and that the invention can be carried out by other means. Also, while it is designed to use the various features and elements in the combination and relations described, some of those may be altered and others omitted without interfering with the more general results outlined, and the invention extends to such use.

Having described my invention, what I claim and desire to secure by Letters Patent is:

1. A paint brush device of the class described, comprising a container having bottom and side walls, a screen member in said container disposed a predetermined distance from said bottom wall and adapted to have paint brushes rest thereupon, a support for said screen member, said support normally resting freely on said bottom wall a handle member, and means including a pivot shaft for rotatably mounting said handle on said support, said handle member comprising a portion above said pivot shaft extending upwardly of said container and a cammed portion below said pivot shaft adjacent to and adapted to contactively engage said bottom wall, the distance between said pivot shaft and said bottom wall being less than the distance between said pivot shaft and said cammed portion whereby upon pivotal movement of said handle in one direction about said pivot shaft, said cammed portion will contactively abut said bottom wall to cause said support to be lifted from said bottom wall, for the purposes set forth.

2. A paint brush device according to claim 1 in which said support for said screen member comprises a rigid member of smaller size than said container so as to be spaced from said side wall thereof.

3. A paint brush device according to claim 1 in which means are provided for normally maintaining said handle member in ineffective position.

4. A paint brush device according to claim 1 in which means including a spring are provided for normally maintaining said handle member in ineffective position, said spring interconnecting said handle member with said support.

5. A paint brush device according to claim 1 in which the bottom edge of said support is notched to greatly reduce the area of direct contact with said bottom wall.

6. A paint brush device according to claim 1 in which the said support is formed from a flat strip of material bent in the shape of a ring with the opposite edges terminating in a pair of flanges extending outwardly from said ring and in which the said handle member is pivotally mounted between said flanges.

7. A paint brush device according to claim 1, in which means are provided for maintaining said screen in fixed attachment with said support whereby said support, said screen member and said handle member may be removed from said container as a unit.

8. A paint brush device of the class described, comprising a container having bottom and side walls, a screen member in said container disposed a predetermined distance from said bottom wall and adapted to have paint brushes rest thereupon, a support for said screen member, said support being formed from a flat strip of rigid material bent into the shape of a ring with the opposite edges terminating in a pair of flanges extending outwardly from said ring, said ring being smaller in diameter than said container so as to be spaced from said side wall, said support having its bottom edge notched to greatly reduce the area of direct contact with said bottom wall, said support being adapted to normally rest freely upon said bottom wall, a handle member, means including a pivot shaft for rotatably mounting said handle on said support between said flanges, said handle member comprising a portion above said pivot shaft extending upwardly of said container and a cammed portion below said pivot shaft adjacent to and adapted to contactively engage said bottom wall, the distance between said pivot shaft and said bottom wall being less than the distance between said pivot shaft and said cammed portion whereby upon pivotal movement of said handle said cammed portion will contactively abut said bottom wall to cause said support to be lifted from said bottom wall for the purposes set forth, means comprising a spring interconnected between said support and said handle member for normally maintaining said handle member in ineffective position, and means for maintaining said screen in fixed attachment to said support whereby said support, said screen and said handle member may be removed from said container as a unit.
